SHOE

Millard S. Peabody, Falmouth Foreside, Maine, assignor to E. E. Taylor Corporation, Freeport, Maine, a corporation of Massachusetts

Application June 15, 1954, Serial No. 30,995

Term of patent 14 years

(Cl. D7—6)

FIG. 3

Fig. 1 is a perspective view of a shoe showing my new design; and

Fig. 2 is a front elevational view thereof.

Fig. 3 is an enlarged fragmentary perspective view of the front portion of the shoe and illustrating the side of the shoe opposite that shown in Fig. 1.

The dominant features of the design reside in the portions shown in full lines.

I claim:

The ornamental design for a shoe, substantially as shown and described.
